UNITED STATES PATENT OFFICE.

JOHN W. OLSSON, OF YORK, PENNSYLVANIA.

TOY VEHICLE.

1,348,577.

Specification of Letters Patent. Patented Aug. 3, 1920.

Application filed November 19, 1919. Serial No. 839,127.

To all whom it may concern:

Be it known that I, JOHN W. OLSSON, a citizen of the United States, residing at York, in the county of York and State of Pennsylvania, have invented certain new and useful Improvements in Toy Vehicles, of which the following is a specification.

This invention relates to a toy vehicle, and its object is to provide a toy vehicle 10 which shall be inexpensive, simple in construction and strong and durable and preferably contain an element or elements simulating a bird, animal or the like which will be put in motion when the vehicle is 15 moving.

In the accompanying drawings,

Figure 1 is a side view and Fig. 2 a plan of the improved vehicle;

Fig. 3 is a vertical sectional view on the 20 line 3—3 of Fig. 1, looking rearwardly; and

Fig. 4 is a fragmentary horizontal section on the line 4—4 in Fig. 1.

The frame structure includes in the preferred form a plate *a* sufficiently wide at its rear portion to form a seat, and having its forward portion constituting a central forward extension *b* of its rearward portion and appreciably narrower than the same; 25 the frame structure also includes two depending brackets *c* rigidly secured to the under side of the seat, as by screws *d*, and having opposed bearing bolts or other studs *e*; the frame structure further includes an inverted substantially T-shaped block *f* 30 whose vertical portion *f'* may be slightly wider than the extension *b* and is secured rigidly to the under side thereof by screws *g*, and whose horizontal portion, forming 35 the arms *h* of the T, projects well beyond the sides of extension *b*.

With the frame thus constructed, the child can sit on the seat portion of the plate *a* and rest his feet, as in coasting, in a more 45 or less comfortable position, on the projections *h* of member *f*.

The sides of the upright portion *f'* of the T offer flat vertical bearing surfaces *i*, the purpose of which will be explained.

50 Wheels *j* are journaled on the studs *e*.

The vehicle is preferably of the dirigible type. To this end there is a steering post *k* having a cross-head or handle *l* rigidly secured to its upper end, and which, penetrating a suitable hole in the extension *b*, has a bearing in the member *f*; that is to

say, the post proper *k* penetrates also said member and at its lower end has a fork shaped enlargement or head *m* which is seated in a socket *n* formed in the under side 60 of the member *f*. In the fork *m*, and on a horizontal pin *o* therein, is journaled the front or steering wheel *p*.

At each side of the vertical portion of the T-shaped member *f* is a transverse horizontal bearing, in the present instance afforded by a screw *q* driven into said member and preferably equipped with a washer *r*. Resting on and having sliding contact with each of these bearings is a forwardly and backwardly moving figure *s* in the form of a plate cut out to represent some bird, animal or the like, the connection between each figure and the bearing being preferably afforded by a longitudinal slot *t* of less width 75 than the washer *r* and receiving the bearing, so that when the screw *q* is driven home the washer will hold the inner flat face of the figure close to the surface *i* of member *f*. The rearward end of each figure is connected by a bolt *u* thereon with an eccentric point on the corresponding wheel *j*. With these figures included in the toy when the latter is in motion the figures will move forwardly and backwardly and at the same 80 time rock on the bearings *q* as their fulcra. All the main elements of the vehicle may be formed of wood.

The frame may also include a metal strap *v* secured to the under side of the seat and 90 having its ends bent downward and secured to the inner faces of brackets *c*. Each bearing device *e* and *u* is preferably a bolt equipped with suitable nuts *e'* *e''* (*u'* *u''*) whereby it is clamped to the member *c* (*s*) 95 which carries it.

So far as I am aware it is new in this art to provide a frame having a top plate wide at the back and formed with a substantially central forward extension of the back portion and also having rigid means depending from the back portion of the plate and an inverted substantially T-shaped rigid means depending from the extension, the arms of the T-shaped means extending beyond the 105 extension of the plate so as to afford foot rests in convenient relation to the plate formed as described. So far as I am aware it is also new in this art to provide a frame structure with a rigid depending forward 110 portion formed with substantially vertical lateral faces, wheel-including supports (as

j, k—m—p) arranged in said frame structure and one being mounted in the depending portion, and vertically moving figures attached to the frame and having lateral vertical faces opposed to and adapted to bear against said vertical lateral faces. It is further new in this art, so far as I am aware, to provide a frame structure having a transverse horizontal bearing, a forwardly and 5 backwardly moving figure resting on and having a sliding contact with said bearing, and fore and aft wheel supports depending from the frame and each including a wheel, said figure being pivotally connected to an 10 eccentric point of one wheel.

Having thus fully described my invention, what I claim as new and desire to secure by Letters Patent is:—

1. A frame including a substantially horizontal plate forming a seat at its rear portion and having its forward portion a substantially central forward extension of the seat and narrower than the same, rigid means depending from the seat part of the plate, 20 a rigid substantially inverted T-shaped member depending from the extension, the arms of the T extending beyond the sides of the extension and forming foot-rests, in combination with wheel-supports arranged in 25 said rigid depending means and member. 30

2. In combination, a frame structure having a rigid depending forward portion

formed with substantially vertical lateral bearing surfaces, wheel-supports arranged in the frame in fore and aft arrangement, 35 one wheel support being mounted in said depending portion, and vertically moving figures attached to the frame and having lateral vertical faces arranged opposite and adapted to bear against said bearing surfaces. 40

3. In combination, a frame structure having a transverse horizontal bearing, a forwardly and backwardly moving figure resting on and having a sliding contact with 45 said bearing, and fore and aft wheel supports depending from the frame and each including a wheel, said figure being pivotally connected to an eccentric point on the wheel.

4. In combination, a frame structure including a seat forming member and forward and rear rigid means depending from said member, the former means having laterally projecting bearings on opposite sides thereof, forwardly and backwardly moving figures 55 resting on and having a sliding contact with the respective bearings, and fore and aft wheel including supports arranged in the respective depending means, each figure being pivotally connected to an eccentric point 60 of the wheel of the rear wheel support.

In testimony whereof I affix my signature

JOHN W. OLSSON.
